United States Patent Office

Des. 203,799

Patented Feb. 15, 1966

203,799

HANDLE

George Gordon Alexander, Sauk Rapids, Minn.

Filed Apr. 5, 1965, Ser. No. 84,611

Term of patent 7 years

(Cl. D93—4)

FIG. 1

FIG. 2

FIG. 3

FIG. 4

FIG. 5

FIG. 1 is a side elevational view viewed from one side of a handle illustrating the embodiment of the invention.

FIG. 2 is a view similar to FIG. 1 viewed from the opposite side of the handle.

FIG. 3 is a view similar to FIGS. 1 and 2 viewed from the top of the handle.

FIG. 4 is a view similar to FIGS. 1, 2 and 3, viewed from the bottom of the handle.

FIG. 5 is an end view of the handle.

The broken line showing of a hammer head throughout the figures is for illustrative purposes only.

I claim:

The ornamental design for a handle, as shown and described.
